(57) **CLAIM**

The ornamental design for a display screen with graphical user interface, as shown and described.

DESCRIPTION

FIG. 1 is a front view of a display screen with user interface showing our new design; and,

FIG. 2 is a front view of a display screen with user interface FIG. 1 shown with additional disclaimed content.

The broken line showing of the remainder of the user interface and display screen is for environmental purposes only and forms no part of the claimed design.

1 Claim, 2 Drawing Sheets

FIG. 1

FIG. 2
